UNITED STATES PATENT OFFICE.

HACKLEY MORRISON, OF RICHMOND, VIRGINIA.

BLANK FEEDING AND CHUCKING DEVICE.

Application filed May 25, 1921. Serial No. 472,455.

To all whom it may concern:

Be it known that I, HACKLEY MORRISON, a citizen of the United States, residing at Richmond, in the county of Henrico and State of Virginia, have invented certain new and useful Improvements in Blank Feeding and Chucking Devices, of which the following is a specification.

This invention relates to automatic machines for operating upon the ends of short cylindrical blanks, such as those from which pipe nipples, stud bolts, etc., are made, and more particularly to the feeding and chucking of the blanks to be operated upon.

The present invention is designed especially for use in connection with automatic machines for finishing the ends of nipple blanks, such, for example, as that shown and described in my copending application Serial No. 366,662, filed March 17, 1920. The invention is not, however, limited to use with machines of this type since it may be employed with advantage in connection with any finishing or threading machine in which there is a vertically reciprocating chuck jaw for moving the blanks to and gripping them in position to be operated upon by the tool.

While in my copending application above identified, I have illustrated an inclined runway for feeding the blanks by gravity to the chucking device, I find that such an arrangement is not wholly satisfactory for all classes of work, and the main object of the present invention is to provide an improved device for positively and accurately feeding the blanks into position to be engaged by the movable jaw of the chuck. A further object is to arrange such a feeding device so that it will cooperate with a stripper of the type shown in the above mentioned application, such feeding device and stripper serving to automatically deliver blanks to and remove them from the chucking device respectively, in proper timed relation.

In order that the invention may be readily understood reference is had to the accompanying drawings forming part of this specification, and in which:

Figure 1 is a vertical transverse section through a machine of the type shown in my prior application, illustrating the feeding in and stripper device in one position;

Figure 2 is a similar view showing the feeding in device and stripper in another position;

Figure 3 is a fragmentary sectional plan view of the machine, parts being in section substantially on the line 3—3 of Figure 1, and other parts being omitted for the sake of clearness; and

Figure 4 is a view similar to Figure 1, but showing a slightly modified construction.

Referring to the drawings in detail, 1 designates the bed of the machine, and 2 the legs or pedestals on which it is supported. 3 indicates a box or receptacle into which the finished blanks are delivered by the stripper, and 4 designates a pair of aligned tools arranged to operate upon the ends of the blank. These tools are here shown as of the type covered by my copending application Serial No. 430,866, filed December 15, 1920, but may, of course, be of any desired type, such as is employed for chamfering, reaming, threading, or other similar operations. The tools 4 are carried by co-axial spindles 5 which are continuously rotated by any suitable mechanism (not shown).

Disposed between the tools 4 is the chucking device which comprises a fixed upper jaw 6 and a movable lower jaw 7. The upper jaw is carried in a suitable yoke 8 supported by posts or standards 9 set into the bed of the machine.

The lower jaw 7 is carried at the upper end of a plunger, which, as shown in the first mentioned above copending application, comprises two sections 10 and 11 separated by a helical spring 12, the whole being enclosed within and slidable through a guide or housing 13. A shield 14 preferably surrounds the upper end of the plunger so as to exclude foreign matter from the guide or housing. The lower end of the plunger section 11 carries a roller 15 which is in engagement with a suitably shaped cam 16 mounted upon a cam shaft 17 journaled in brackets 18. From an inspection of Figures 1 and 2 it will be seen that as the cam 16 revolves the jaw or chuck member 7 is vertically reciprocated, the cam being so shaped as to produce a substantial "dwell" at both the upper and lower limits of movement of the plunger.

Referring to Figures 1, 2 and 3, the improved feeding in and stripper device forming the subject of the present invention comprises a transversely disposed plate or bar 19 mounted for reciprocation upon the bed 1 adjacent the chuck, and secured and guided as by means of clips 20. To the bar 19 are secured, at a suitable distance apart, a pair of standards or brackets 21, 22, having at their upper ends horizontal arms 21^a and 22^a, such arms being provided with a slot or a series of perforations, as shown in Figure 3. Secured to the arm 21^a is the stripper, comprising a pair of bars or members 23 held in suitable spaced relation by means of bolts passing through certain of the holes formed in the arm 21^a. Similarly secured to the arm 22^a is the feeding in device or carrier comprising a pair of spaced bars or members 25. It will be understood that, as shown in Figure 3, the bars 23 and 25 are similarly spaced and are so arranged as to straddle the jaw 7 of the chuck. In other words, a vertical plane passing through the center of the chuck jaw 7 passes midway between the two pairs of bars 23 and 25.

The bars 23 are preferably set at a slight incline, as shown in Figures 1 and 2, and their inner ends are somewhat up-turned as indicated at 24. The bars 25 may or may not be horizontal, as shown, but they are formed adjacent their inner ends so as to provide a curved seat or pocket 26 of such shape and size as to constitute a cradle in which a blank can snugly lie.

The bar 19 supporting the stripper and carrier above described is arranged to be reciprocated transversely of the bed 1 as by means of a lever 27 pivoted at 29 and engaging the bar 19 at its upper end, such lever passing through a slot 28 formed in the bed. The lower end of the lever 27 is attached to one end of a helical spring 30, the other end of which is secured to the frame of the machine. Between the pivot 29 and spring 30 the lever 27 carries a roller 31 which is arranged to engage a cam 32 rigidly mounted on the cam shaft 17. This cam 32 is also so shaped as to produce a "dwell" at each end of the limit of movement of the bar 19, and the cams 16 and 32 are mounted on the shaft 17 in such angular relation as to produce movements of the chuck jaw, carrier and stripper, properly timed as hereinafter described.

Assuming the parts to be in the position shown in Figure 2, the operator places a blank in the pocket or cradle 26, such blank being properly centered by means of a suitable stop (not shown), so that it projects an equal distance on either side of the chuck device. The chuck jaw 7 then descends and the carrier 25 moves inwardly toward the chuck until it reaches the position shown in

Figure 1. In this position the chuck jaw 7 is at the lower limit of its movement, and the pocket 26 carrying the blank lies immediately above it. As in my copending application first above mentioned, the upper end of the chuck jaw 7 has a seat 7^a formed therein of such size and shape as to receive the blank being operated upon. Then, after the parts have reached the position shown in Figure 1, the carrier remains stationary for a moment while the plunger and chuck member 7 ascend, the seat 7^a engaging under the blank and lifting it out of the pocket 26. The chuck member 7 continues to ascend, thus elevating the blank and finally gripping it between the upper and lower chuck members in position to be operated upon by the rotary tools 4, the cam 16 permitting the chuck jaw 7 to remain in such position for a suitable interval. After the chuck jaw 7 has removed the blank from the pocket 26 the bar 19 is again shifted toward the right, thus moving the carrier 25 away from the chuck and at the same time bringing the curved end 24 of the stripper into a position in which it straddles the jaw 7. By this time the jaw 7, bearing the finished blank, is descending, and since, as above described, the stripper has been projected into the path of the descending blank, such blank is transferred from the seat 7^a of the jaw 7 on to the stripper as the seat moves past, and is thus removed from the chuck. The finished blank thereupon rolls down the inclined bars 23 of the stripper and falls into the receptacle 3.

It will thus be seen that the carrier 25 and stripper 23 move simultaneously and alternately toward and from the chuck device, and such movement takes place in proper timed relation with the movements of the jaw member 7, so that as the operator places the blanks in the pocket or cradle 26, when the carrier is in the position shown in Figure 2, such blanks are successively and automatically carried into position to be engaged by the ascending chuck jaw, are elevated by such jaw into position to be operated upon, are then lowered by the jaw, and are finally removed from the jaw by the stripper.

The purpose of the cushion spring 12 interposed between the plunger sections 10, 11 is to produce a yielding gripping action of the chuck and thus avoid crushing the blanks.

While in Figures 1 and 2 I have shown the stripper and carrier as mounted upon the same supporting bar or base, and thus movable together, and have illustrated such bar as moved in one direction by a cam and in the other direction by a spring, the benefits and advantages of my invention can be secured without employing this specific construction. Many other details of construction, within the spirit of the invention, will

readily suggest themselves to a skilled mechanic, and in Figure 4 I have illustrated one other such construction which may be employed to advantage. Referring to this figure, it will be seen that the stripper and carrier 33 and 35 are substantially similar to the corresponding parts numbered 23 and 25 in the other views, and that the ends 34 and 36 of these members are shaped substantially as above described. Instead of being secured to a single reciprocating bar, however, the stripper and carrier are shown in Figure 4 as secured to the upper ends of independent levers 37 and 38 pivoted at 39 and 40, respectively, to fixed brackets 41 and 42, these levers being provided at their lower ends with weights 43 and 44, respectively. A pair of plungers 45 and 46 slide freely through guides 47 and 48 carried by the machine frame and are disposed to engage the levers 37 and 38, respectively, at a point below their pivots. The plungers 45 and 46 carry at their inner ends rollers 49 and 50, which engage suitably shaped independent cams 51 and 52 carried by the cam shaft 17.

The levers 37 and 38 are thus moved in one direction by gravity acting upon the weights 43 and 44, and in the other direction by the plungers 45 and 46, the cams 16, 51 and 52 being so shaped and angularly disposed as to effect the movement of the stripper, carrier, and chuck jaw in proper timed relation to carry out the same cycle of operations as above described in connection with the other figures.

While I have shown the stripper and carrier in Figures 1 and 2 as formed of two separate pairs of bars, it is obvious that these devices may be formed from two continuous strips or bars extending from the standard 21 to the standard 22, and suitably bent or shaped to perform the functions described.

It will thus be seen that I have provided an exceedingly simple, positive and effective device for automatically feeding blanks to and removing them from an automatic chucking device, and it is thought that the many advantages of my invention will be readily appreciated without further discussion.

What I claim is:

1. In a machine for manufacturing cylindrical articles, the combination with a rotary tool and a chuck device for gripping the blank at a point between its ends and holding it in alinement with the axis of said tool, said chuck device comprising a pair of jaws one of which is movable toward and away from the other in a direction at right angles to said axis, means for periodically moving said jaw, a carrier for conveying a blank to such chuck device, said carrier having means to receive and wholly support the

blank, and means for bodily reciprocating said carrier in synchronism with said movable jaw.

2. In a machine for manufacturing cylindrical articles, the combination with a tool 70 and a chuck device for holding the blank in horizontal position, said chuck device comprising a fixed upper and movable lower jaw, means for vertically reciprocating said lower jaw, a carrier for conveying a blank 75 to said chuck device, said carrier having means for wholly supporting the blank, and means for bodily moving said carrier toward said chuck device as the lower jaw descends, so as to carry the blank into a position above such jaw when the latter has reached its lower limit of travel, and sustain it in such position as the lower jaw moves upward, and means for moving said carrier away from the chuck device after said lower 80 jaw has ascended a predetermined distance.

3. In a machine for manufacturing cylindrical articles, the combination with a rotary tool, and a chuck device for holding the blank in horizontal position, said chuck device comprising a fixed upper and movable lower jaw, means for vertically reciprocating said lower jaw, a carrier for conveying a blank to said chuck device, said carrier having a blank receiving and supporting 90 pocket, and means for reciprocating said carrier in definite timed relation with said movable jaw so as to bring said pocket into a position above said lower jaw when the latter is at the lower limit of its travel. 100

4. In a machine for manufacturing cylindrical articles, the combination with a rotary tool, and a chuck device for holding the blank in horizontal position adjacent said tool, said chuck device comprising a fixed upper and movable lower jaw, said lower jaw having at its end a seat adapted to receive the blank, means for vertically reciprocating said lower jaw, a carrier for wholly supporting a blank, said carrier having a blank receiving pocket, and means for reciprocating said carrier in a plane lying between the upper and lower limits of travel of said seat, and in definite timed relation with said movable jaw so as to bring said pocket alternately into and out of a vertical plane through said seat and tool axis. 110

5. In a machine for manufacturing cylindrical articles, the combination with a 120 rotary tool, and a chuck device for holding the blank in horizontal position adjacent said tool, said chuck device comprising a fixed upper and movable lower jaw, said lower jaw having at its end a seat adapted to receive the blank, means for vertically reciprocating said lower jaw, a carrier for supporting a blank, said carrier comprising a pair of spaced members and having a blank receiving pocket formed in said mem- 125 130

bers, and means for periodically shifting said carrier so as to bring said pocket and seat into the same vertical plane, with said members disposed one on each side of the 5 path of travel of said lower jaw.

6. In a machine for manufacturing cylindrical articles, the combination with a rotary tool, and a chuck device for holding the blank in horizontal position adjacent 10 said tool, said chuck device comprising a fixed upper and movable lower jaw, said lower jaw having at its end a seat adapted to receive the blank, means for vertically reciprocating said lower jaw, a carrier for 15 wholly supporting a blank, and automatic means, operating after the said lower jaw has reached its lowermost position, for shifting said carrier toward the chuck device in such manner as to bring the blank 20 supported thereby into a position directly above said lower jaw, whereby, when said lower jaw ascends, the seat formed therein engages the blank and lifts it from the carrier.

25 7. In a machine for manufacturing cylindrical articles, the combination with a rotary tool, and a chuck device for holding the blank in horizontal position adjacent said tool, said chuck device comprising a fixed upper and movable lower jaw, said lower jaw having at its end a seat adapted to receive the blank, means for vertically reciprocating said lower jaw, a carrier for wholly supporting a blank, automatic means, 30 operating after the said lower jaw has reached its lowermost position, for shifting said carrier toward the chuck device in such manner as to bring the blank supported thereby into a position directly above said 35 lower jaw, whereby, when said lower jaw ascends, the seat formed therein engages the blank and lifts it from the carrier, and automatic means for subsequently shifting said carrier away from the chuck device 40 before said lower jaw descends.

45 8. In a machine for manufacturing cylindrical articles, the combination with a rotary tool, and a chuck device for holding the blank in horizontal position adjacent said 50 tool, said chuck device comprising a fixed upper and movable lower jaw, said lower jaw having at its end a seat adapted to receive the blank, means for vertically reciprocating said lower jaw, a carrier for supporting a blank, said carrier comprising a

pair of spaced members adapted to straddle said lower jaw, and having a pocket formed in said members, in which pocket the blank rests, and automatic means for shifting said carrier so as to bring said pocket into the 60 same vertical plane with said seat after said lower jaw has reached its lowermost position, permitting said carrier to so remain for a definite time interval, during which said lower jaw rises and the seat 65 therein receives and lifts the blank from the pocket, and subsequently shifting said carrier away.

9. In a machine for manufacturing cylindrical articles, the combination with a 70 rotary tool, and a chuck device for holding the blank in horizontal position adjacent said tool, said chuck device comprising upper and lower jaws, said lower jaw having at its upper end a seat adapted to receive the blank, means for vertically reciprocating said lower jaw, a stripper and a blank carrier mounted on opposite sides of the chuck device for movement toward and from the same, means for shifting the carrier toward the chuck device while the lower jaw is in its lowermost position so as to bring the blank supported thereby directly over said seat, whereby, when said lower jaw ascends, the blank is lifted thereby from said carrier, and moved into position to be operated upon by the tool, and means for then automatically shifting the carrier away and projecting the stripper into a position below and in the path of 80 the finished blank as the lower jaw, bearing such blank in its seat, descends, so that the finished blank is brought into engagement with and deposited upon said stripper, and thus removed.

95 10. In a machine for manufacturing cylindrical articles, the combination with a tool mounted to rotate about a horizontal axis, of a chuck adjacent said tool and comprising an upper fixed and lower movable jaw, a carrier for wholly supporting a blank, means for shifting said carrier so as to cause it to carry a blank into a position immediately beneath said upper jaw, and means for causing said lower jaw to rise and first lift the blank from said carrier, and then grip it between itself and said upper jaw.

In testimony whereof I affix my signature.
HACKLEY MORRISON.
